CLAIM

The ornamental design for a spindle for a recreational vehicle, as shown and described.

DESCRIPTION

FIG. 1 is a top plan view of a recreational vehicle spindle showing my new design;

FIG. 2 is an outboard side elevation view thereof;

FIG. 3 is a bottom plan view thereof;

FIG. 4 is an inboard side elevation view thereof;

FIG. 5 is a front elevation view thereof; and

FIG. 6 is a rear elevation view thereof.

FIG. 7 is a front perspective outboard side view thereof; and,

FIG. 8 is a rear perspective inboard side view thereof.

1 Claim, 5 Drawing Sheets
